(57) **CLAIM**

The ornamental design for a bottle, as shown and described.

DESCRIPTION

FIG. 1 is a perspective view of a bottle showing the new design;

FIG. 2 is a right side elevation view of the bottle of FIG. 1; FIG. 3 is a left side elevation view of the bottle shown in FIG. 1;

FIG. 4 is a front side elevation view of the bottle shown in FIG. 1;

FIG. 5 is a rear elevation view of the bottle shown in FIG. 1;

FIG. 6 is a top plan view of the bottle shown in FIG. 1; and, FIG. 7 is a bottom plan view of the bottle shown in FIG. 1. The broken lines shown illustrate portions of the bottle that form no part of the claimed design.

1 Claim, 4 Drawing Sheets
